[57] CLAIM

The ornamental design for a fishing reel body, as shown.

DESCRIPTION

FIG. 1 is a top, front and right side perspective view of a fishing reel body, showing our new design;

FIG. 2 is a rear, top and left side perspective view thereof;

FIG. 3 is a front, bottom and right side perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a left side elevational view thereof; and,

FIG. 9 is a right side elevational view thereof.

The broken line showing of environment in all views is for illustrative purposes only and forms no part of the claimed design.

FIG. 1

FIG. 2

FIG. 3

FIG. 4

FIG. 5

FIG. 6

FIG. 7

FIG. 8

FIG. 9
